ROLLING SUPPORT FOR GARMENT HANGERS

Harold A. Reich, 305 W. 86th St., New York 24, N.Y.

Filed July 29, 1964, Ser. No. 81,062

Term of patent 3½ years

(Cl. D80—8)

FIG. 1 is a front elevation of a rolling support for garment hangers embodying my new design.

FIG. 2 is a top plan view of the same.

FIGS. 3 and 4 are opposite end views of the support. I claim:

The ornamental design for a rolling support for garment hangers, substantially as shown.
